UNITED STATES PATENT OFFICE.

ROBERT A. ALDINGER, OF TOWN LINE, NEW YORK.

HIGHWAY SNOWPLOW.

Application filed March 25, 1924. Serial No. 701,806.

To all whom it may concern:

Be it known that I, ROBERT A. ALDINGER, a citizen of the United States, residing at Town Line, in the county of Erie and State 5 of New York, have invented certain new and useful Improvements in a Highway Snowplow, of which the following is a specification.

This invention relates to snow plows and 10 has more particular reference to a device of this character that is adapted to be associated with a motor vehicle truck at a point preferably upon the forward end thereof whereby the snow may be advantageously 15 removed from highways for allowing traffic to pass in an uncongested manner thereover.

The primary object of this invention is to 20 provide a snow plow wherein the same constitutes a power plant to be disposed upon the body of the motor truck and to drive at a relatively high speed a bladed fan at the front end of the truck which serves as a means for beating the snow to opposite sides of the road for quickly clearing the 25 same therefrom.

A further object of the invention is to 30 provide a snow plow wherein the same includes a shovel or scoop at a point forwardly of the fan for directing the snow to a point to be acted upon by said propeller.

A still further object is to provide a means 35 wherein the action of the fan may be reversed in order to at all times direct the snow away from the driver of the truck.

With the foregoing and other objects in 40 view as the nature of the invention will be better understood the same comprises the novel form, combination and arrangement of parts hereinafter more fully described, shown in the accompanying drawing and claimed.

In the drawing wherein like reference characters indicate corresponding parts throughout both of the views—

Figure 1 is a top plan view of a motor 45 vehicle truck equipped with a snow plow constructed in accordance with the present invention, and

Figure 2 is a side elevational view thereof.

Now having particular reference to the 50 drawing 5 designates generally a motor vehicle truck of any conventional design.

My invention per se constitutes the provision of a desirable frame designated generally 6 and including suitable inclined side bars 7—7 that are connected at their inner ends in a manner as designated by the refer-

ence characters 8—8 to the forward ends of the chassis bars of the vehicle truck frame. The forward ends of the side bars are supported off of the ground through the medium of suitable caster wheels 9. Disposed between these bars 7—7 at the front ends thereof is a scoop or shovel 10 relatively inclined as shown. The forward end of this shovel is at a point slightly spaced from the road surface as clearly indicated in Figure 2, and journaled suitably at opposite ends of this shovel or scoop 10 are horizontally arranged worm conveyors or shafts 11—11 that are continuously rotated in the manner to be presently described in order to prevent the accumulation of the snow or ice at opposite sides of the shovel or scoop 10.

Disposed upon the body of the truck 5 in the manner preferably as indicated is a suitable form of reversible high speed valve-in-head motor 12, the forward end of the crank shaft of which is operatively connected to a horizontal shaft 13 that extends parallel with the longitudinal axis of the truck frame and is suitably journaled intermediate its ends as shown in both of the figures. Between this shaft 13 and the crank shaft of the motor is a suitable reversing mechanism 14 whereby the direction of rotation of the crank shaft of said motor 12 may be reversed whenever desired. This shaft 13 is further equipped at a point preferably slightly forwardly of the drivers seat of the truck with a brake mechanism 15 which includes an actuating lever 16 whereby the rotation of the shaft 13 may quickly stop when the motor is cut off for obvious purposes.

Operatively connected at one end through the medium of a universal joint 17 to the forward end of the shaft 13 and at its opposite end within a suitable bearing 18 carried by upstanding arms 19 of the side bars 7—7 of the frame 6 is the shaft of a rotary bladed fan 20. The shaft of the fan has connection with the worm shafts 11—11 through the medium of belts 21—21.

It will thus be apparent from the foregoing description when considered in conjunction with the accompanying drawing that as the truck 5 is being moved over the highway an operation of the motor 12 will control the rotation of the fan 20, whereby the snow that is carried above the road surface by the scoop or shovel 10 will be blown and beat to either side of the road for mani-

2
festly completely clearing the highway of snow, thereby allowing traffic to pass there-over.

The specific operation together with numerous advantages of a snow plow of this character will be at once appreciated by those skilled in the art, and even though I have herein shown and described the most practical embodiment of the invention with which I am at this time familiar it is nevertheless to be understood that minor changes may be made in the invention without departing from the spirit and scope of the appended claims.

15 Having thus described my invention what I claim as new and desire to secure by Letters Patent is:—

1. In a snow plow, a frame adapted to be pivotally mounted upon the forward end of said vehicle, a frame embodying spaced parallel downwardly inclined arms, an open ended snow scoop arranged between the free ends of the arms and inclined downwardly, a bearing supported above said frame, a 20 horizontal driven shaft journaled in said bearing, an exposed rotary bladed fan carried by said shaft, the blades of said fan sweeping across the open inner end of said

scoop when the fan is operated, and rotary screws mounted in said scoop adjacent the 30 opposite side walls thereof.

2. A snow plow attachment for a vehicle comprising a frame adapted to be pivotally supported upon the forward end of a vehicle, said frame embodying a pair of forwardly and downwardly inclined side bars, a pair of upwardly diverging arms carried by said side bars, a bearing at the upper end of said arms, said bearing connecting said upper ends together, a forwardly and downwardly inclined scoop secured between the free ends of said side bars, said scoop being open at its front and rear ends, a second bearing adapted to be carried by said vehicle, a driven shaft rotatably mounted in said 40 bearings, an exposed bladed rotor carried by said shaft and having its blades spaced above said side bars and adapted to sweep across the inner open end of said scoop, conveyor screws mounted for rotation within said 45 scoop adjacent the vertical side walls of the latter, and driving connections between said screw and said driven shaft.

In testimony whereof I affix my signature.

ROBERT A. ALDINGER.
